CLAIM

We claim the ornamental design for a menstrual product applicator, as shown and described.

DESCRIPTION

FIG. 1 is a front perspective view of the menstrual product applicator.

FIG. 2 is a front view of FIG. 1.

FIG. 3 is a right side view of FIG. 2.

FIG. 4 is a back side view of FIG. 2.

FIG. 5 is a left side view of FIG. 2.

FIG. 6 is a top view thereof; and,

FIG. 7 is a bottom view thereof.

The broken lines in the figures depict environmental subject matter only and form no part of the claimed design.

1 Claim, 3 Drawing Sheets
